UNITED STATES PATENT OFFICE.

EDWARD M. STANNARD, OF BRISTOL, WISCONSIN.

FOLDING FURNITURE.

No. 921,801.

Specification of Letters Patent.

Patented May 11, 1909.

Application filed April 6, 1908. Serial No. 425,306.

To all whom it may concern:

Be it known that I, EDWARD M. STANNARD, residing in Bristol, in the county of Kenosha and State of Wisconsin, have invented new 5 and useful Improvements in Folding Furniture, of which the following is a description, reference being had to the accompanying drawings, which are a part of this specification.

10 My invention has relation to improvements in folding furniture, more especially, although not necessarily, adapted for use in connection with a folding cot.

One of the important objects of the invention is to provide a construction whereby sagging of the canvas is readily taken up through the medium of a simple and easily operated arrangement and combination of parts.

20 A further object resides in the particular arrangement and combination of parts, whereby the structure is rendered capable of being folded into a compact bundle, for convenient shipment.

25 The invention furthermore contemplates as an object a construction combining comfort, strength and simplicity.

With the above, and other incidental objects, in view the invention consists of the devices and parts, or their equivalents, as hereinafter set forth.

In the accompanying drawings, Figure 1 is a side elevation showing my improvements in the form of a cot, the cot being set up ready 35 for use; Fig. 2 is an end view of Fig. 1, parts broken away; Fig. 3 is a fragment of the center of the cot, looking down upon the top thereof; Fig. 4 is a view illustrating the method of folding the cot for transportation;

40 Fig. 5 is a side elevation of a modified form of the invention applied as a cot, the said cot being shown set up ready for use; Fig. 6 is a view of one end of this cot partly folded; Fig. 7 is a plan view of a fragment of the center 45 of the cot shown in Fig. 5; Fig. 8 is a view showing in detail the spreading mechanism, the lower beam and other parts being in section; Fig. 9 is a side view of one of the socket plates for receiving the outer end of one of 50 the spreader arms; and Fig. 10 is a front view of said plate.

The drawings show my improved arrangement and combination of parts employed in such manner as to form a cot, when the parts 55 are adjusted to the position illustrated in Fig. 1. The top of the cot is, as usual, of a

canvas 11, the side edges of which are attached to the side pieces constituting portions of the frame work. Each of these side pieces is composed of two sections 12, 12 60 hinged together at their inner meeting ends. The hinged joint is such that the two members or sections of each side, will be brought together, when the cot is folded for transportation or shipment. I employ as one 65 form of hinge, the specific structure shown more especially in Figs. 1 and 3 of the drawings. Each of these hinges consists of two side plates 13, 13, the under edges of which are connected centrally by an elongated web 70 14, and the upper edges of which are connected at the ends by less elongated webs 15, 15. A transverse brace strip 16 also connects the upper edges of these plates at the centers of said edges. The inner ends of the side pieces 75 12 of the frame are passed in between the side plates 13 of the hinges, and are pivoted therebetween on transverse pivot pins 17, 17. By this construction of hinge, when the side pieces are straightened out and the cot ad- 80 justed to the position shown in Fig. 1, the ends of the side pieces have firm bearings against the under web 14 and the end webs 15, 15 said webs, therefore, resisting any 85 tendency of the side pieces to turn on their pivots. These webs therefore act to maintain the straightened out positions of the side pieces when the cot is set up. The said webs, in connection with the upper central brace strips 16, also serve to strengthen the hinge. 90

The supporting legs at the front and rear of the cot are indicated by the numeral 18. Secured to one side of the upper end of each of these legs is a plate 19 projecting upwardly beyond the upper end of the leg. One side 95 edge of each plate is provided with a flange 20 projecting outwardly therefrom at right angles thereto, the upper end of said flange joining a horizontal flange 21 along the upper edge of the plate, the two flanges forming in 100 connection with the plate a socket. Secured to the opposite side of the upper end of each leg is a hinge plate 22, the upper end of each plate being provided with an extension 23 projecting inwardly at right angles and piv- 105 oted to one of the sections 12 of the side of the frame by a pivot pin 24. The side member or section 12 of each side of the cot passes between the plate 19 and the hinge plate 22, when the cot is adjusted to its up- 110 right position ready for use.

In securing the canvas 11 to the side sec-

tions 12, said side sections are placed beneath the side edges of the canvas, and said canvas then secured to the side sections by means of tacks, nails, or equivalents. The side edges of the canvas with the attached side members 12 of the frame are then turned under, so that what were originally the upper sides of the side members 12 became the under sides thereof, when the cot is set up. It will be seen that the canvas centrally at opposite edges thereof is cut out, as indicated by the numeral 25. These cut out portions facilitate the folding of the canvas, and also prevent bulging thereof when folded.

The spreading mechanism for each pair of end legs consists of a lower horizontal bar 26 and two spreader arms 27, 27. The horizontal bar is provided at opposite ends, upon its under side, with angle strips 28, 28, the depending lips of said strips adapted to engage back of one side of a metal band 29 bent partly around each leg. The leg also has a cut-away portion 30 leading down to and back of the band to facilitate the insertion of the depending lips of the angle strips. Through the center of each bar 26 is an opening 31 which at its upper end is enlarged into a recess into which is seated a metallic plate 32 having a threaded opening therethrough in continuation of the opening 31. A screw 33 passes through opening 31 and engages the threaded opening of plate 32, and the upper end of this screw has a rigid engagement with the bottom piece of a U-shaped bracket 34. Supported in the side pieces of this bracket is a pin 35 which forms a pivot for the inner ends of the two spreader arms. The outer ends of the spreader arms are beveled off and are adapted to engage the socket plates 19, as clearly shown in the drawings. By turning one of the screws 33 in one direction the bracket 34 to which the upper end of said screw is attached is raised, and this necessarily has the effect of causing the arms 27 to spread outwardly and their outer ends to firmly engage the plates 19. When it is desired to disengage the spreader arms, the screw 33 is turned in the opposite direction, which of course permits of the outer ends of the spreader arm being turned out of engagement with the plates 19.

As hereinbefore explained, the sections 12 forming the sides of the frame are first placed beneath the side edges of the canvas, and the canvas attached thereto. After attachment in this manner the canvas and the sections 12 are turned under, so that the legs 18 of the sections 12 depend from said sections. It is of course desirable and preferred that the legs 18 incline outwardly so as to form a firm support. There is therefore left sufficient play between the upper ends of the legs and the under sides of the sections 12 so as to permit the legs to assume this inclination, the upper ends of the legs being beveled so as to

engage squarely against the under sides of the sections 12 when thus thrown out, and the lower ends of the legs being beveled in the opposite direction so as to bear firmly on the floor or other horizontal support. After the legs are thus adjusted to their upright positions, the spreading mechanism is then adjusted to place. This is accomplished by first passing the depending lips of the angle plates 28 into engagement with the bands 29. The outer ends of the spreader arms are then adjusted to the socket plates 19, and the screw 33 turned in the direction to force the outer ends of said spreader arms outwardly into firm engagement with the socket plates. The spreading mechanism for the opposite pair of legs is then adjusted in the same manner, and the cot is ready for use. By the adjustment outwardly of the spreader arms in the manner described, it is evident that the canvas is rendered taut, and that should said canvas through continued use of the cot sag at any point, particularly at the center where such sagging usually occurs, the said sagging may be readily taken up by turning the screws 33 in the proper direction to cause a further outspreading of the arms 27.

When it is desired to take down the cot and fold it for shipment or otherwise, the spreading mechanism is first removed in an obvious manner. The sections 12 are then turned outwardly to the original position in which the elongated web 13 of the central hinges are uppermost. The legs are then turned downwardly against the sections 12, and said sections 12 turned toward each other on the central hinges. The ends of the thus folded structure are then turned inwardly, as clearly shown in Fig. 4, and the spreader mechanism may then be placed upon the canvas as indicated in Fig. 4, said figure showing one of the spreading mechanisms placed upon the canvas. The other spreading mechanism may now be similarly disposed, and the entire structure rolled up into a compact bundle.

The modified construction shown particularly in Figs. 5 and 6 of the drawings differs from the structure illustrated upon Sheet 1 only in respect to the form of central hinge employed and also the employment of central supporting legs. These central supporting legs are indicated by the numeral 36. Each of these central legs is provided with one of the metallic bands 29 for the engagement therewith of the depending lips of the angle strips 28 of the horizontal bar 26 of the central spreading mechanism, which central spreading mechanism is identical with the spreading mechanism employed for the end legs. These central legs 36 are also provided at their upper ends with the socket plates 19 for the reception therein of the outer ends of the spreader arms. By the provision of these central legs 36 a different

form of central hinges are necessary than is employed in the Sheet 1 form of construction. This hinge consists of a T-shaped metallic piece 37, the stem of the T being 5 secured against the outer sides of the central legs 36, and the heads of the T's being adjacent to the outer sides of the sections 12 of the side pieces of the frame, and pivoted thereto on pivot pins 38, 38. Both the 10 upper ends of the central socket plates 19 and the upper ends or heads of the T-shaped hinges 37 project above the upper ends of the central legs 36, and consequently the inner ends of the sections 12 of the frame, 15 when the cot is set up, are received between these upwardly extending or projecting portions of the parts referred to. In folding this form of cot together after removing the spreading mechanism the side pieces and 20 side edges of the canvas are turned outwardly, as in the case of the Fig. 1 form of construction so as to cause the legs to point upwardly. The end legs are then folded down, and the entire cot folded at the central 25 hinges. The side edges of the thus folded cot are then turned inwardly, as illustrated in Fig. 6 of the drawings, said figure showing one of said side edges thus folded. The spreading mechanism is then laid upon the 30 canvas in the same manner as illustrated in Fig. 4, and the structure now rolled into a compact bundle.

While I prefer that the frame work be so adjusted together and employed in connection with the canvas as to form a cot, yet I do not wish to be understood as limiting myself to this particular adaptation of the invention, as it is obvious that the same construction of legs and spreading mechanism 40 may be employed in connection with other forms of folding furniture, such for instance as a folding table, or in connection with a folding bath tub. When employed in the former relation, the canvas would be supplanted by a wooden top piece, and when employed as a folding bath tub a cup shaped form of canvas will be substituted for the flat canvas arrangement of the cot.

What I claim as my invention is:

50 1. In folding furniture, the combination of legs provided at their upper ends with sockets, a horizontal bar having its opposite ends connected to the legs, a member above the bar, adjustable means engaging the bar and said member, whereby the member may be raised or lowered, and spreader arms having their inner ends pivoted to the member and their outer ends adapted to engage the sockets of the legs.

60 2. In folding furniture, the combination of legs provided at their upper ends with sockets, a horizontal bar, means at opposite ends of said bar for detachably connecting said ends to the legs, a member above the bar, adjustable means engaging the bar and said mem-

ber, whereby the member may be raised or lowered, and spreader arms having their inner ends pivoted to the member and their outer ends adapted to engage the sockets of the legs.

70 3. In folding furniture, the combination of legs provided at their upper ends with sockets, loops secured to said legs at points between the ends thereof, a horizontal bar provided at opposite ends with depending lips 75 adapted to detachably engage the loops, a member above the bar, adjustable means engaging the bar and said member, whereby the member may be raised or lowered, and spreader arms having their inner ends pivoted to the member and their outer ends adapted to engage the sockets of the legs.

80 4. In folding furniture, the combination of legs, socket plates secured to the upper ends of said legs, a horizontal bar having its opposite ends connected to the legs, a member above the bar, adjustable means engaging the bar and said member, whereby the member may be raised or lowered, and spreader arms having their inner ends pivoted to the 85 member, and their outer ends adapted to engage the socket plates.

90 5. In folding furniture, the combination of plates provided at their upper ends with sockets, a horizontal bar having an opening 95 vertically therethrough, the ends of said bar being connected to the legs, a screw having a threaded connection with said opening, a member above the bar and engaged by the upper end of the screw, whereby said member 100 may be adjusted upwardly or downwardly, and spreader arms having their inner ends pivoted to the member and their outer ends 105 engaging the sockets of the legs.

110 6. In folding furniture, the combination of legs, socket plates secured to the upper ends of said legs, a horizontal bar provided at opposite ends with depending lips, loops connected to the legs at points between the ends of said legs, said loops adapted to be detachably engaged by the depending lips, a member above the bar, adjustable means engaging the bar and said member, whereby the member may be raised or lowered, and spreader arms having their inner ends pivoted to the member and their outer ends 115 engaging the socket plates.

120 7. In folding furniture, the combination of legs, a socket plate connected to one side of each leg and projecting above the upper end 125 of said leg, a hinge plate connected to the opposite side of each leg and projecting above the upper end of said leg, a horizontal bar having its opposite ends connected to the legs, a member above the bar, adjustable means engaging the bar and said member, whereby the member may be raised or lowered, and spreader arms having their inner ends pivoted to the member and their outer ends adapted to engage the socket plates.

8. In folding furniture, the combination of side pieces, legs connected at their upper ends to said side pieces, a member connecting the lower portions of the legs together, and means connected to the upper portions of the legs and in engagement with the member for spreading apart laterally of the upper ends of the legs while the lower portions are held from spreading by the member.
- 10 9. In folding furniture, the combination of side pieces, legs connected at their upper ends to said side pieces, a member connecting the lower portions of the legs together, a spreader connected to the upper portions of the legs, and an adjustable connection between the member and the spreader for spreading apart laterally of the upper ends of the legs while the lower portions are held from spreading by the member.
- 15 10. In folding furniture, the combination of side pieces, legs pivoted at their upper ends to said side pieces, and provided at their upper ends with sockets, a horizontal bar having its opposite ends connected to the legs, a member above the bar, adjustable means engaging the bar and said member, whereby the member may be raised or lowered, and spreader arms having their inner ends pivoted to the member, and their outer ends adapted to engage the sockets of the legs.
- 20 11. In folding furniture, the combination of side pieces, each side piece composed of two sections having their inner ends hinged together, legs pivoted at their upper ends to said side pieces, and provided at their upper ends with sockets, a horizontal bar having its opposite ends connected to the legs, a member above the bar, adjustable means engaging the bar and said member, whereby the member may be raised or lowered, and spreader arms having their inner ends pivoted to the member, and their outer ends adapted to engage the sockets of the legs.
- 25 12. In folding furniture, the combination of side pieces, each side piece composed of two sections having their inner ends hinged together, the hinged construction being such that said sections are capable of being swung or folded together, or turned outwardly in horizontal alinement, legs provided at their upper ends with sockets, and having their upper ends pivoted to the sections of the side pieces, the pivots being such as to permit the legs to be swung from an upright position up to and against the under sides of the sections of the side pieces, a horizontal bar having its opposite ends connected to the legs, a member above the bar, adjustable means engaging the bar and said member, whereby the member may be raised or lowered, and spreader arms having their inner ends pivoted to the member, and their outer ends adapted to engage the sockets of the legs.
- 30 13. In folding furniture, the combination of side pieces, each side piece composed of two sections having their inner ends hinged together, the hinged construction being such that said sections are capable of being swung or folded together, or turned outwardly into horizontal alinement, legs provided at their upper ends with sockets, and having their upper ends pivoted to the sections of the side pieces, the pivots being such as to permit the legs to be swung from an upright position to and against the under sides of the sections of the side pieces, a horizontal bar having its opposite ends detachably connected to the legs, said bar provided with a vertical opening therethrough, a screw having a threaded connection with said opening, a member carried at the upper end of the screw, and spreader arms pivoted to said member, and having their outer ends adapted to engage the sockets of the legs.
- 35 14. In folding furniture, the combination of side pieces, each side piece composed of two sections, a hinge for connecting the inner ends of the two sections of each side piece together, each hinge consisting of side plates between which the inner ends of the sections are pivoted, a central elongated web connecting the lower edges of the side pieces centrally, upper webs connecting the upper edges of the side pieces at opposite ends thereof, and a brace strip connecting the upper edges of the side pieces centrally, legs pivoted at their upper ends to the sections of the side pieces, and provided at said upper ends with sockets, a horizontal bar having its opposite ends connected to the legs, a member above the bar, adjustable means engaging the bar and said member, whereby the member may be raised or lowered, and spreader arms having their inner ends pivoted to the member, and their outer ends adapted to engage the sockets of the legs.
- 40 15. In folding furniture, the combination of side pieces, legs pivoted at their upper ends to the outer ends of said side pieces, said legs provided at their upper ends with sockets, central legs pivoted at their upper ends to the centers of the side pieces, and provided at their upper ends with sockets, a horizontal bar for each pair of legs, said bar having its opposite ends connected to the respective legs of a pair, a member above each bar, means engaging the bar and said member, and adapted when operated in one direction to raise said member, and when operated in the opposite direction to lower said member, and spreader arms pivoted to the member at their inner ends, and adapted to have their outer ends engaging the sockets of the legs.
- 45 16. In folding furniture, the combination of side pieces, each side piece consisting of two sections, hinges for the inner ends of said sections, one portion of the hinge being
- 50 55 60 65 70 75 80 85 90 95 100 105 110 115 120 125 130

5 pivoted to one section and another portion of the hinge being pivoted to the other section, the hinged construction being such that said sections are capable of being folded or
10 swung together, or turned into horizontal alinement with each other, legs pivoted at their upper ends to the outer ends of said sections of the side pieces, said legs provided at their upper ends with sockets, central legs provided at their upper ends with
15 sockets, said legs connected to the central hinges, the pivots of all of said legs being such as to permit the legs to be swung from an upright position to and against the under sides of the sections of the side pieces, a horizontal bar for each pair of legs, the

opposite ends of said bar being connected to the respective legs of a pair, a member above each bar, means engaging the bar and said member, and adapted, when operated in one 20 direction, to raise said member, and, when operated in the opposite direction, to lower said member, and spreader arms pivoted to each member at their inner ends, and adapted to have their outer ends engage the sockets of the legs. 25

In testimony whereof, I affix my signature, in presence of two witnesses.

EDWARD M. STANNARD.
